UNITED STATES PATENT OFFICE.

LEONARD BUSHNELL, OF NEW BEDFORD, MASSACHUSETTS, ASSIGNOR TO
PIERCE AND BUSHNELL, OF SAME PLACE.

DESIGN FOR WATCH-CASES.

Specification forming part of Design No. **7,104**, dated January 13, 1874; application filed December 1, 1873.
[Term of Patent 7 years.]

To all whom it may concern:

Be it known that I, LEONARD BUSHNELL, of New Bedford, in the county of Bristol and State of Massachusetts, have invented a new Design for a Watch-Case, of which the following is a specification:

The nature of my design is fully represented in the accompanying photographic illustrations, to which reference is made.

My design is produced by the association of the following elements:

A represents a body or back board; B, a

shell; and C C, ornamental chains. The body may be covered with velvet, and may be provided with a hook, p, for suspending the case; but I lay no claim to the mechanical construction of said case, nor the material employed.

What I do claim is—

The design for a watch-case, as herein shown and described.

LEONARD BUSHNELL.
